UNITED STATES PATENT OFFICE.

ALBERT GERSTENDORFER AND MAX GERSTENDORFER, OF NEW YORK, N. Y.

DESIGN FOR AN ADVERTISING-SIGN.

SPECIFICATION forming part of Design No. 29,854, dated December 20, 1898.

Application filed November 12, 1898. Serial No. 696,305. Term of patent 3½ years.

To all whom it may concern:

Be it known that we, ALBERT GERSTENDORFER and MAX GERSTENDORFER, residing in the borough of Manhattan, city, county, and State of New York, have invented and produced a new and original Design for an Advertising-Sign, of which the following is a full, clear, and exact description.

The leading feature of our invention is an advertising-sign of essentially the representation shown in the accompanying drawing, which illustrates an advertising-sign embodying our design.

In the drawing, a is a base surmounted by a pedestal b, which is surmounted by a figure c of the general shape of a bath-tub in miniature.

What we claim is—

The design for an advertising-sign, substantially as herein shown and described.

ALBERT GERSTENDORFER.
MAX GERSTENDORFER.
